ALFRED T. TAYLOR, OF BEVERLY HILLS, CALIFORNIA, ASSIGNOR TO METRO-GOLDWYN-MAYER CORPORATION, OF CULVER CITY, CALIFORNIA, A CORPORATION OF NEW YORK

METHOD OF TREATING SOUND RECORDS AND RECORDS PRODUCED THEREBY

Application filed January 31, 1930. Serial No. 425,035.

This invention relates to a method of treating sound records, and particularly sound records bearing thereon variable density impressions representing sound waves or oscillatory currents of varying frequencies. The invention particularly relates to a method of treating continuous sound records photographically recorded on a transparent base. The invention also relates to improved sound records which may be obtained by carrying out the method embraced by this invention.

Sound records of the character particularly adapted for treatment in accordance with the method to be described hereinafter and embraced by this invention, are records produced by a modulated light upon a sensitive film emulsion on a substantially transparent base. Records of this character are generally known as variable density records, and comprise striations extending transversely to the longitudinal axis of the continuous film. Said striations occur in the continuous film spaced from each other at varying distances, said distances or periods depending upon the speed or rate of movement of the film during recording and the frequency of the recorded oscillations.

In this manner the spacing of said striations is a function of the frequency of the sounds recorded on the film. By passing such a variable density record in front of a narrow slit through which a constant beam of light is being passed, the light is modulated, and in this manner a modulated light is projected upon a photo-electric or other light sensitive cell adapted to generate an oscillatory current comparable to the frequencies recorded upon the record and to the frequencies of the sounds originally recorded thereon.

When films of the hereinabove described character are connected to each other, a splice results which is more opaque than the rest of the film. Furthermore, the splice is of appreciable width and when such splice passes in front of a constant light source, it modifies the light passing through the film and causes the photo-electric cell or other reproducing mechanism to be influenced by said splice. In this manner a splice creates an audible click

or noise as the film is passed through the reproducing mechanism, and very often interferes with the reproduction of the record. Such clicks and splice marks are of high amplitude and it is impossible at the present time to transfer a record from a film onto a wax recording without causing such maximum amplitude changes to influence the wax recordings and very often render them useless.

When a splice sound of high amplitude is reproduced the vibration set up in the stylus recording the sounds upon a wax record is sufficient to cause the stylus to leave its individual groove and engage with or cross an adjoining groove.

Heretofore, extraneous sounds accidentally recorded upon a continuous film record of the character described hereinabove could not be removed without cutting the film and splicing it, such splices as has been explained before, being disadvantageous. If it was desired to insert a particular section of sound record onto a continuous film, it was necessary to make two splices, one at each end of the insertion made into the continuous film.

An object of this invention is to disclose and provide a method for making a quiet splice in a sound recording.

Another object is to disclose and provide a method whereby continuous sound recordings may be corrected without the creation of spliced sound records.

Another object is to disclose and provide a method of splicing films which is substantially invisible and which does not create extraneous sounds when the record is reproduced.

A still further object is to disclose and provide a method of inserting sound records into continuous films bearing sound records thereon, without introducing mechanical or extraneous noises.

Another object is to disclose and provide an improved type of connected sound record.

Another object is to disclose and provide an improved type of spliced sound record which does not create extraneous noises during reproduction.

A still further object is to disclose and pro-

vide a sound record having insertions made therein, said insertions being incapable of causing extraneous mechanical sounds during reproduction.

5 Other objects, uses and advantages of this invention will become apparent to those skilled in the art from the following detailed description of a method in its preferred and modified forms, and of the result which may 10 be attained thereby.

In describing the invention, reference will be had to the appended drawings, in which:

Fig. 1 is a front view of a combined picture and sound recording, showing the film or record produced in accordance with this invention.

Fig. 2 is an enlarged view of a splice connecting two continuous sound records.

20 Fig. 3 shows two continuous films bearing sound records connected in accordance with this invention.

Fig. 4 represents a continuous sound record in which an extraneous sound has been recorded.

25 Fig. 5 represents a sound record such as that shown in Fig. 4, which has been treated in accordance with the method of this invention so as to remove the extraneous sound.

By the term "splicing" or "spliced" as used 30 herein, reference is made to the act of scraping, cutting and cementing film together, whether said film bears thereon a sound record, a picture record, or a combination of both picture and sound records. During 35 splicing operations the emulsion on one of the films is generally scraped off and occasionally one or more of the ends of the film records which it is desired to connect are beveled. A cementing fluid is then applied, 40 said fluid generally comprising or containing amyl-acetate or other suitable solvent which permits the cellulosic backings to weld together. Generally, the total width of the 45 splice ranges from about 1/10th to 2/10ths of an inch.

As shown in Fig. 2, the continuous film 1 is cemented or spliced to a continuous film 2 so as to form an overlapping joint 3. The 50 films 1 and 2 bear a sound record thereon, the film 1 bearing thereon a longitudinal strip 4 having transverse striations 5 of greater density than the intermediate portions 6 or the portion 7 which does not bear any striations at all. The horizontal striations 5 represent the nodes of an oscillatory current, the spacing being dependent upon the frequencies of the oscillatory current. The area 7 merely bears a record of the carrier wave or unmodulated light which normally passes through the light valves (used in recording) when an oscillatory current is not passing through said light valves. The areas, such as 7, give rise to what is known as surface or ground noises.

65 It will be seen that at 3 two sharp lines

extend through the sound record, these lines representing the edges of the overlapped film. Such lines will, during reproduction, cause the photo-electric cell, or other reproducing means, to be energized thereby causing a sharp aperiodic click to be reproduced, such click or noise being of volume usually equal to the normal level of the film record. Such noises are highly undesirable, particularly as a thousand-foot reel often contains as many as one hundred such splices, each of which reproduces as a loud clicking noise. One of the objects of this invention is to permit a splice or joint to be made which will not cause the film to give rise to such extraneous noise.

In carrying out the method of my invention, a film may be joined or spliced in the ordinary manner and, therefore, the film will first assume the character shown in Fig. 2. A section is then cut from the joined films 1 and 2, the section taking the form of one half cycle of a sine wave, the wave having a height or amplitude equivalent to the width of the sound record 4, and a period or length equivalent to a frequency of 25 cycles, or any other frequency substantially below the normal range of audibility. More correctly, the section takes the form of four-sixths of a complete sine wave composed of one maximum positive value and two maximum negative values, such curve starting and terminating at zero. The maximum amplitude of the section thus cut from the film should occur at the splice 3 so that the overlapping or doubled thickness of film in the splice is removed in the sound record proper 4. Preferably, the sine wave section thus cut from the film includes a datum section extending into the film and away from the sound record so as to form shoulders 8 with an edge 9 parallel to the longitudinal axis of the sound record 4, but spaced therefrom.

The edges 10 and 11 of the section thus cut out of the film are in the form of a half cycle sine wave, the edge 10 extending from one side of the record to the other side and assuming the form of one-half cycle (from a maximum negative value to a maximum positive value) of a sine wave of a frequency below normal audibility, whereas the edge 11 is in the form of the other half of a cycle of such a sine wave (from the maximum positive value to the maximum negative value).

A section 12 identical to the segment cut out of the joined films 1 and 2 and described hereinabove, is also cut out of a single separate piece of film, said section being either transparent or of a density substantially equivalent to the carrier wave or surface noise density 7 of the record 4. The section 12 thus cut from a separate piece of film is then introduced into the aperture cut from the joined films 1 and 2, said section 12 fitting exactly into said aperture. A small

quantity of a cellulosic solvent such as for example, amyl, butyl or ethyl acetate or the like may then be rubbed over the insertion and over the joint or crevice between the 5 films 1 and 2 and the section 12. The film cement is drawn into the joint by capillary action, and welds the abutting edges of section 12 and the edges of the films 1 and 2, becoming an integral part of the continuous 10 film, said cement being substantially transparent. The line along which the joint occurs is normally substantially invisible and, therefore, does not reproduce when the films thus joined and treated are passed through 15 a reproducing apparatus. Even though the joint would be opaque, no audible sound would result, particularly if the density of the two joined film records and the inserted section is substantially the same, as the frequency of the reproduced sound wave of the 20 section 12 is below the normal range of audibility.

Attention is called to the fact that the section 12 needs preferably be in the form of an 25 incomplete sine wave. For example, if the edges 10 and 11 are straight so that the section 12 assumes the form of an equi-lateral triangle, and if the joints formed at those edges are opaque, then there may be a tendency 30 for said joint to reproduce a harmonic of the frequency represented by the amplitude and period of the section thus inserted.

If the edges 10 and 11 are sine curves, however, and even though the section 12 were 35 completely opaque, then only the fundamental of the frequency represented by the section 12 would be reproduced, and inasmuch as said frequency is below the normal range of audibility, no extraneous noise would be 40 reproduced when such a film is passed through a reproducing mechanism.

The method described hereinabove is not limited in its application to splices or joints in the film. If, for example, a film such as 45 the sound record illustrated in Fig. 4 is encountered, said sound record bearing thereon a record of a desired frequency represented by the striations 13, in which an extraneous noise has been inadvertently recorded as indicated at 14, such record may be corrected so 50 that the extraneous noises or sound recorded at 14 is eliminated. This can be accomplished in the following manner:

A sine wave section is cut out of the film or 55 sound record shown in Fig. 4, said section comprising a front edge 15 having the form of half a cycle of a sine wave of a frequency below normal audibility, and extending from one edge of the sound record to the other so 60 as to have an amplitude equivalent to the width of the sound record, and a rear edge 16 in the form of the other half of the cycle of such sine wave.

The crest of the sine wave section represented by the edges 15 and 16 may be sepa-

rated by a distance Y equivalent to the length of the record embracing the false note or extraneous noise, such as the recording 14. The entire section thus cut out preferably also includes the datum portion 17, although such datum portion may be eliminated, the elimination of the datum portion 17 making it more difficult to insert and retain the very narrow pointed ends of the sine wave section cut out and subsequently inserted. 75

A section 18 identical in contour and length to the section thus cut out of the film or sound record is then cut out of another sound record bearing thereon the required striations or frequencies. For example, the 80 section 18 preferably bears thereon a variable density record of a note or sound having the same frequency as the sound recorded and indicated at 13. The record on the section 18 may be indicated by the striations 13'. The 85 section 18 is then inserted carefully into the aperture cut into the sound record illustrated in Fig. 4, and welded in place by the application of a suitable film cement such as amyl- 90 acetate.

It is to be understood that the joints formed by the insertion of the incomplete sine curve sections into the apertures cut into the sound records are abutted joints, preferably, and not overlapped joints, so that the thickness 95 of the film is not varied. As a result of the hereinabove described operations, a record such as is shown in Fig. 5 results, from which the extraneous sounds or noises, such as those indicated by the recording at 14 have been removed. 100

It is to be understood that the method described hereinabove is not only applicable to the performance of the acts and the attainment of the results described in the above examples, but may also be applied in numerous other instances. The method may be employed in overcoming splice noises, removing surface noises, removing a portion of a record, removing an error in a record, removing a portion of the record and inserting a section which bears no recording, removing damages in the record, removing a portion of the sound record and inserting a correction, or making other changes in the recordings produced originally. 110

Sound recordings are preferably originally recorded on continuous films, but reproducing apparatus is available for reproducing not only continuous film records, but also wax or disc recordings. Heretofore it has been normally impossible to produce a wax record from a reproduction of a film record. The reason for this is that sudden extraneous noises of high amplitude recorded upon the continuous film or carried by it, as for example, splice noises, cause the stylus used in engraving the sound record upon the disc to vibrate through an amplitude sufficiently great to intersect and cross an adjoin- 115 120 125 130

ing groove in the spiral recording being cut in the disc. It is likely then that when such a record is played the reproducer needle will not track properly in the groove and will 5 continue either to play in one groove steadily or jump over the adjoining groove entirely.

If the original sound recording on the continuous film is treated in accordance with the methods embraced by this invention, then 10 said continuous sound record may be safely employed in the reproduction of the sounds for recording on a disc, cylinder or other wax record.

When the method embraced by this invention is applied to sound records carried by a continuous film which also carries picture records (such as the film shown in Fig. 1), then it is preferable to position the datum section away from the perforated edge of the 20 film and permit the crest of the sine curve sections cut out and inserted into the sound record to adjoin that edge of the record which in turn adjoins the perforations. This arrangement and position of the sections does 25 not decrease the strength of the film and obviates the tendency for the film to separate or tear at that portion where such sections have been cut out and inserted.

The methods embraced by this invention 30 may be varied somewhat as will be apparent to those skilled in the art, and the invention is not limited to the precise sequence of operations, length and form of the sections cut out or inserted into the sound record, or the 35 precise purpose of said acts specifically mentioned hereinabove. The invention includes all such changes and modifications as come within the scope of the appended claims.

I claim:

40 1. A method of treating spliced continuous sound records, comprising removing a section of the sound record at a splice, said section being in the form of a half cycle sine curve with its crest at the splice, the sine 45 curve having an amplitude substantially equivalent to the width of the sound record and a period equivalent to a vibration of frequency below normal audibility, and then inserting and cementing a section of film 50 similar in contour to the removed section into said sound record.

2. A method of treating spliced continuous sound records, comprising removing a 55 section of the sound record at a splice, said section being in the form of a half cycle sine curve with its crest at the splice, the sine having an amplitude substantially equivalent to the width of the sound record and 60 a period substantially equivalent to a vibration of frequency below normal audibility, cutting a section identical in contour and size to said removed section from a separate sound record, and inserting and cementing 65 said separate section into the aperture

formed by the removal of said first section from said record.

3. A method of treating continuous films bearing sound recordings thereon so as to remove extraneous recordings therefrom, comprising cutting a section from said sound record, said section being in the form of a half cycle sine curve with its crest at the point where the extraneous record is located, said sine curve having an amplitude substantially equivalent to the width of the sound record and a period equivalent to a vibration of frequency below normal audibility, cutting a separate section from a film free from extraneous sound records, said separate section being identical in size and configuration to the section removed from said sound record being treated, and inserting and cementing said separate section in the aperture formed in said sound record to be treated. 75

4. A method of treating continuous films bearing sound recordings thereon and including extraneous recordings, comprising removing a section of the sound record to be treated, said section being in the form of a half cycle sine curve with its crest at the point where the extraneous sound records are located, said sine curve having an amplitude substantially equivalent to the width of the sound record and a period equivalent to a vibration below normal audibility, cutting a section from a separate film bearing a desired sound record thereon, said separate section being identical in size and configuration to the first section removed from the film to be treated, and inserting and cementing said separate section in the aperture formed in the sound record to be treated. 90

5. A continuous sound record including a section of different material bodily inserted 105 thereinto, said section having the form of a half cycle sine wave.

6. A sound record comprising a continuous strip of material having a variable density sound record thereon, and an insertion made 110 in said record, said insertion having the form of a half cycle sine wave.

7. A spliced sound record comprising two continuous strips of material having variable density sound records thereon connected together, and an insertion of half cycle sine wave form carried by said strips at their point of connection. 115

8. A spliced sound record comprising two continuous strips of material having variable density sound records thereon connected together, and an insertion of half cycle sine wave form made in said sound records at their point of connection, the crest of said sine wave insertion being substantially in 120 alignment with said splice.

9. A sound record comprising a continuous strip of material having variable density sound records thereon, and an insertion made, in said sound record, said insertion having 130

the form of a half cycle sine wave and bearing a variable density sound record.

10. A sound record comprising a continuous strip of material having a variable density sound record thereon, and an insertion made in said sound record, said insertion having the form of a half cycle sine wave and bearing a variable density sound record in synchronism with the record on said continuous strip.

11. A sound record including a section inserted therewith, said section having the form of an incomplete sine wave having a frequency below normal audibility, and an amplitude equivalent to the width of the sound record.

Signed at Culver City, California this 18th day of December, 1929.

ALFRED T. TAYLOR.
